OIL BURNER NOZZLE

Filed Feb. 21, 1927

FIG. 2.

INVENTOR.

Harry Barley.

BY
Carlo P. Griffis.

ATTORNEY.

UNITED STATES PATENT OFFICE

HARRY BARLEY, OF SAN FRANCISCO, CALIFORNIA, ASSIGNOR TO ENTERPRISE OIL BURNER COMPANY, OF SAN FRANCISCO, CALIFORNIA, A CORPORATION OF CALIFORNIA

OIL-BURNER NOZZLE

Application filed February 21, 1927. Serial No. 169,716.

This invention relates to an oil burner nozzle, and its object is to prevent the oil from passing from the nozzle after the supply of oil has been turned off.

turned on for the burner to be lighted it is an advantage to have the pipe 1 full of oil right up to the nozzle 3.

Having thus described my invention, what I desire to secure by Letters Patent of the United States is as follows, but modifications may be made in carrying out the invention as shown in the drawing and in the above particularly described form thereof, within the purview of the annexed claim:

An oil burner nozzle of the class described comprising in combination an oil supply pipe and a bell shaped nozzle thereon, a smaller supply nozzle having a nipple on one end adapted to engage threads in the oil supply pipe, the other end of said smaller nozzle extending into the bell shaped nozzle approximately the full length thereof, said smaller openings having laterally directed openings adjacent the bottom of said bell shaped nozzle, and a spring pressed ball in said smaller nozzle adapted to close said openings when the nozzle is inactive.

In testimony whereof I have hereunto set my hand this 11th day of February, A. D. 1927.

HARRY BARLEY.

It will be understood by those skilled in the art that oil fires cause considerable trouble because of the fact that there is always a lagging over of the fire after the oil pump has been shut off, for the reason that the pump is usually a foot or two from the end of the pipe and the oil remaining in the pipe continues to drip at the end of the nozzle, and sometimes causes trouble.

With the present invention the oil stops burning as soon as the pressure pump supplying the nozzle with oil stops, or if gravity is used to supply the burner with oil, as soon as the oil valve is closed.

Other objects of the invention will be apparent as the description proceeds.

An embodiment of the invention is shown in the accompanying drawings in which the same reference numeral is applied to the same portion throughout the several figures of the drawings and of which there may be modifications.

Figure 1 is a vertical sectional view through the nozzle,

Figure 2 is a front elevation of the oil burner nozzle.

The numeral 1 indicates the oil supply pipe which extends to any convenient source of supply, either a pump or gravity pipe sub-line leading to a place of storage for the oil.

This oil supply pipe has a bell-shaped nozzle 2 thereon, and inside this bell-shaped nozzle there is a smaller supply nozzle 3. This nozzle 3 has a threaded nipple 4 which extends into the pipe 1 and it is bored to receive

a ball 5, a plug 6, a light spring 7, and the threaded retaining plug 8. Holes 9 and 10 are provided at the base of the nozzle 3 for the oil to escape from, and the ball 5 is normally held against the bore for the nipple 4

with sufficient force to prevent the escape of oil except when pressure is applied thereto. This will prevent any oil leakage when the pump is turned over, or when the valve which supplies the oil to the nozzle is closed.

At the same time when the oil is freshly
